ELECTROLYTIC PRODUCTION OF
ALKANESULFONIC ACIDSBruce K. Brown, Skokie, Ill., assignor to Standard
Oil Company, Chicago, Ill., a corporation of In-
dianaNo Drawing. Application June 26, 1946,
Serial No. 679,563

10 Claims. (Cl. 204—79)

1

This invention relates to an electrolytic process for the oxidation of alkyl disulfides. More particularly it relates to a process for the preparation of alkanesulfonic acids by the anodic oxidation of sulfonic acid solutions of alkyl disulfides.

Although numerous chemical methods have been proposed for the oxidation of organic sulfur compounds such as alkyl disulfides to sulfonic acids, it has been found that they frequently result in over-oxidation to produce sulfuric acid or yield considerable quantities of lower oxidation products such as sulfoxides and sulfones together with the desired sulfonic acids. Moreover, said chemical methods entail costly equipment and are not readily adaptable to continuous processing. I have discovered a smooth electrolytic method for the oxidation of alkyl disulfides to produce sulfonic acids in good yields.

One object of my invention is to provide an electrolytic process for the oxidation of alkyl disulfides. Another object is to provide an electrolytic process for the oxidation of alkyl disulfides, in which process a sulfonic acid or a mixture of sulfonic acids is employed as a solvent for the alkyl disulfide. Another object of my invention is to provide an electrolytic process for the oxidation of alkyl disulfides wherein the initial electrolyte consists essentially of a sulfonic acid. These and other objects of my invention will become apparent from the ensuing description thereof.

It has been observed by Fichter and Wenk that diphenyl disulfide can be oxidized to benzenesulfonic acid at a platinum anode in an electrolyte consisting of glacial acetic acid and concentrated hydrochloric acid (Ber. 45, 1376-1383 (1912)). However, these investigators point out (loc. cit., page 1383) that when dibenzyl disulfide was electrolytically oxidized, benzyl disulfoxide was obtained rather than benzylsulfonic acid. It was surprising, therefore, to find that when sulfonic acids are employed as solvents for alkyl disulfides, the resultant solutions can be smoothly oxidized to yield alkanesulfonic acids at the anode of an electrolytic cell.

The term "alkyl disulfide" as used in this specification and the appended claims is intended to denote a disulfide wherein at least one sulfur atom is linked directly to the carbon atom of an aliphatic chain.

Suitable dialkyl disulfide feed stocks include dimethyl, methyl ethyl, diethyl, methyl propyl, dipropyl, dicyclohexyl, dicetyl, and dilauryl disulfides. The feed stock may be a pure com-

2

ound or a mixture of compounds, optionally in admixture with substances, such as paraffin hydrocarbons which are not normally oxidized to an appreciable extent under the conditions employed in my process. I prefer to employ dialkyl disulfide charging stocks, particularly those containing no substituents in the alkyl groups. Moreover, it is highly desirable to use symmetrical dialkyl disulfides, viz., those containing two identical alkyl groups, since they yield only one sulfonic acid upon electrolytic oxidation.

A suitable feed stock is a mixture consisting essentially of dialkyl disulfides of the type obtained as a by-product in the extraction of mercaptans from petroleum distillates with a caustic-solutizer solution followed by regeneration of the solution in the presence of an oxidation catalyst to produce a mixture of dialkyl disulfides which are separated from the caustic solution by settling or by extraction with a solvent, such as petroleum hexane, naphtha, or the like. Either the crude disulfides or a fraction thereof can be oxidized by my technique.

The extraction of petroleum distillates with caustic-solutizer solutions has been described by D. L. Yabroff and E. R. White (Ind. Eng. Chem. 32, 950-953 (1940)) and has been reviewed by V. A. Kalichevsky and B. A. Stagner ("Chemical Refining of Petroleum"—revised edition—1943, pp. 218-220). The production of disulfides by catalytic oxidation of mercaptans (present as mercaptides) in caustic-solutizer solutions has been described by J. P. O'Donnell (The Oil and Gas Journal, pp. 45-47 (July 1, 1944)).

The sulfonic acid employed as the solvent and initial electrolyte in the process of my invention can be the same as or different from the sulfonic acid or acids produced by the electrolytic oxidation of the alkyl disulfide feed stock. However, in the interests of avoiding possible difficulties in separating the sulfonic acid produced in my process from the sulfonic acid employed as the solvent, it is expedient to employ as the solvent a sulfonic acid identical with the one produced in the anodic oxidation process. The employment of aromatic sulfonic acids as solvents and electrolytes in my process is not excluded, as methods are known for separating aromatic sulfonic acids from alkanesulfonic acids and these may be applied to separate the aromatic sulfonic acid solvent from the alkanesulfonic acids produced by the electrolytic oxidation of a dialkyl disulfide or the electrolytic oxidation of an alkyl aryl disulfide.

55 The concentration of alkyl disulfide in the

sulfonic acid solvent may vary from about 1 percent by weight up to the limit of solubility of the disulfide in the sulfonic acid. Ordinarily I employ solutions containing about 15 weight percent of disulfide or even less, for example about 10 weight percent. The water content of the sulfonic acid employed as the solvent and initial electrolyte in the present process can be varied over a wide range, for example between about 1 and about 25 weight percent, based on the weight of said sulfonic acid, e. g., about 15 weight percent. However, since it is commercially desirable to produce alkanesulfonic acids containing as little water as possible, it is preferable that the solution being electrolyzed contain not more than about 10 weight percent of water initially.

The electrolytic oxidation of sulfonic acid solutions of alkyl disulfides may be effected by means of direct current, alternating current or mixed current. Practical, although not necessarily limiting, voltages for my process range from about 1 to about 10 volts. I prefer to avoid relatively high current densities above about 0.02 ampere per square cm., when direct current is employed, especially for the electrolytic oxidation of lower dialkyl disulfides containing not more than about 4 carbon atoms in the molecule. In the electrolytic oxidation of these lower dialkyl disulfides it has been observed that the use of alternating current of low current densities below about 0.1 amp. per square cm. results in smooth conversion of the feed stock to alkanesulfonic acid accompanied by relatively little over-oxidation to sulfuric acid, as will be brought out more fully in the examples below.

Electrolytic oxidation of alkyl disulfides in accordance with this invention has been effected at about room temperature, but temperature is not a critical variable in this process and can be varied over a considerable range both below and above room temperature, for example, between about 10° F. and about 170° F. Desirable temperatures fall within the range of about 90 to about 150° F.

Alkanesulfonic acids, especially in aqueous solutions, are corrosive materials and care should accordingly be exercised in the choice of materials used for the construction of the electrolytic cell employed for their production, as well as for auxiliary equipment, such as feed and discharge conduits, separating vessels, fractionating and storage equipment, etc. Equipment for handling alkanesulfonic acids can be made of or lined with glass or other resistant ceramic materials, structural carbon, stainless steels or noble metals such as gold, silver and the like.

Platinum electrodes have been employed in practicing the process of my invention, but other electrode materials may be employed, e. g., carbon, gold, or other conductors which suffer no appreciable attack by the sulfonic acids under the electrolysis conditions.

The following examples are intended to illustrate but not to limit my invention.

Example 1

The electrolytic oxidation cell consisted of a platinum vessel serving both as a container for the electrolyte and as the anode and, suspended therein, an alumina diaphragm containing a platinum cathode. The electrolyte was a mixture of 85 weight percent of alkanesulfonic acids containing between 1 and 4 carbon atoms in the alkyl group (average molecular weight about 115) and 15 weight percent of water. This electrolyte was saturated with dimethyl disulfide to produce a

solution wherein the solute concentration was approximately 5 weight percent. This solution was anodically oxidized with direct current for 20 hours at the ambient temperature, employing an average of 9 volts and 0.1 amp. As a result, methane-sulfonic acid was formed, as measured by titration by aqueous caustic, at a cell efficiency of 37.8 percent, based on the acid only.

Example 2

The cathode of the cell employed in Example 1 was replaced by a larger one. The solvent employed in Example 1 was saturated with diethyl disulfide to yield a solution thereof having a solute concentration of approximately 10 weight percent. This solution was subjected to electrolysis with direct current for 24 hours at room temperature, 6 volts and 0.29 amp. to produce ethanesulfonic acid at a cell efficiency of 58.6 percent. No undesirable effects, such as reduction of diethyl disulfide to ethyl mercaptan, were observed during the electrolysis.

Examples 3 and 4

The apparatus comprised a totally enclosed all glass cell, provided with a reflux condenser, stirrer, fused-in current leads, and concentric platinum electrodes. The solvent was ethanesulfonic acid containing approximately 20 weight percent of water. The ethanesulfonic acid employed had an average of molecular weight of 108.4 and contained 96.99 weight percent of pure ethanesulfonic acid and 0.66 weight percent of sulfuric acid. This solvent was saturated with diethyl disulfide to produce a solution having a solute concentration of approximately 12.9 weight percent. The following tabulation presents the operating conditions employed and the results obtained.

Example	3	4
Type of current	D. C.	A. C.
Electrolyte acid	Ethanesulfonic.	Ethanesulfonic.
Disulfide feed	diethyl.	diethyl.
Current density, amps./cm. ²	0.0125	0.10.
Faradays, total	0.18	0.75
Voltage, average	3.0	
Sulfonic acid yield	2.1 g.	2.37 g.
Sulfuric acid yield	0.72 g.	0.18 g.
Moles H ₂ SO ₄ per Faraday	0.16	0.002
Ratio sulfonic/sulfuric acid	2.9	13.6
Current efficiency	80%	17%

Although the above examples illustrate batch operations, my invention is not thus limited, since the electrolytic oxidation cells can be designed and arranged for continuous operation with continuous or intermittent introduction of a sulfonic acid solution of alkyl disulfide to one or a series of cells and continuous or intermittent withdrawal of sulfonic acid-enriched electrolyte from the cell or from one of the series of cells. When the electrolytic oxidation is effected in a series of cells with passage of partially oxidized solutions of alkyl disulfides from cell to cell in the series, different operating conditions may be employed in different cells in order to obtain maximum current efficiency.

The sulfonic acid may be recovered as pure acid by adjusting cell conditions and feed proportions so that all the water and disulfide are used up in the electrolysis, the cell effluent then being substantially pure sulfonic acid.

It is contemplated that the addition of small proportions (about 0.001 to about 1 weight percent) of oxidation promoters to the cell electrolyte may be beneficial, for example promoters

such as ceric sulphate, vanadium sulphate and the like.

I claim:

1. A process for the production of an alkane-sulfonic acid which comprises subjecting a solution of a dialkyl disulfide having 1 to 4 carbon atoms, inclusive, in the alkyl group in an electrolyte consisting essentially of an alkane-sulfonic acid containing between about 1 and about 25 weight percent by weight of water to direct current electrolysis at a temperature between about 10° F. and about 170° F., at a voltage between about 1 and about 10 volts and at a current density not exceeding about 0.02 ampere per square centimeter.

2. The process of claim 1 wherein the disulfide is diethyl disulfide.

3. The process of claim 1 wherein the disulfide is dimethyl disulfide.

4. A process for the production of an alkane-sulfonic acid which comprises electrolyzing a solution of an alkyl disulfide in an electrolyte consisting essentially of a sulfonic acid containing between about 1 and about 25 percent by weight of water at an oxidation temperature between about 10° F. and about 170° F. and at a voltage between about 1 and about 10 volts.

5. The process of claim 4 which is conducted with direct current.

6. The process of claim 4 which is conducted with alternating current.

7. The process of claim 4 wherein the alkyl disulfide contains 1 to 4 carbon atoms, inclusive, per alkyl group.

8. A process for the production of an alkane-sulfonic acid which comprises electrolyzing a solution of an alkyl disulfide containing 1 to 4 carbon atoms, inclusive, per alkyl group in an electrolyte consisting essentially of a sulfonic acid containing between about 1 and about 25 percent by weight of water by means of alternating current at a temperature between about 10° F. and about 170° F., at a voltage between about 1 and about 10 volts and at a current density not exceeding about 0.1 ampere per square centimeter.

9. The process of claim 8 wherein the disulfide is diethyl disulfide.

10. The process of claim 8 wherein the disulfide is dimethyl disulfide.
